(57) **CLAIM**

I claim, the ornamental design for a housing for containing a sensing mechanism, as shown and described.

DESCRIPTION

FIG. 1 is a perspective view of a housing for containing a sensing mechanism, showing our new design in an exemplary embodiment;

FIG. 2 is a front view of the embodiment shown in FIG. 1; FIG. 3 is a back view of the embodiment shown in FIG. 1; FIG. 4 is a side view of the embodiment shown in FIG. 1; FIG. 5 is another side view of the embodiment shown in FIG. 1;

FIG. 6 is a top plan view of the embodiment shown in FIG. 1; and,

FIG. 7 is a bottom plan view of the embodiment shown in FIG. 1.

The broken lines are for environmental purpose only and form no part of the claimed design.

The dash-dot lines are boundary lines delineating claimed subject matter within the dash-dot lines from unclaimed, unshaded subject matter outside of the dash-dot lines.

Also, references to "side," "top," "bottom," "front," and "back" in the Figure Descriptions are not necessarily meant to require any specific orientation of the article as viewed. A molded cover according to the claimed design may be used in any orientation.
